(57) **CLAIM**

The ornamental design for a secure electronically controlled wallet device, as shown and described.

DESCRIPTION

FIG. 1 is a top plan view of the secure electronically controlled wallet device in a closed configuration;

FIG. 2 is a right-side elevational view thereof;

FIG. 3 is a left-side elevational view thereof;

FIG. 4 is a bottom plan view thereof;

FIG. 5 is a front elevational view thereof;

FIG. 6 is rear elevational view thereof; and

FIG. 7 is a perspective view thereof from the top front right; and,

FIG. 8 is a perspective view of the secure electronically controlled wallet device in an open configuration from the top right.

The broken lines showing features inside the secure electronically controlled wallet device in FIG. 8 depict environment only and form no part of the claimed design.
